UNITED STATES PATENT OFFICE

FRAZER W. GAY, OF NEWARK, NEW JERSEY

HOT WATER STORAGE FOR POWER GENERATION

Application filed April 28, 1930. Serial No. 447,921.

This invention relates to a novel method of generating power for supplying peak loads involving the use of a storage tank or underground storage reservoir, a charging boiler and a utilizing steam turbine. The advantages of such a storage plant and the disadvantages of methods now commonly used, are fully explained in my pending patent application Serial No. 446,489.

10 It is an object of my invention to utilize the major part of the heat stored in a high pressure storage reservoir in the form of hot water, in such a manner that steam is supplied to the various stages of a steam turbine at substantially constant temperature and pressure and at a rate proportional to the requirements of the load.

15 It is a further object of this invention to provide a series of vaporization chambers through which the stored hot water passes on its way to the cold well. The pressures of these several vaporization chambers are maintained at successively lower temperatures and pressures. A portion of the hot water as it passes through these chambers, flashes into steam, extracting heat from the water in its passage, so that the water when it leaves the last such vaporization chamber 20 has a temperature below the boiling point. The steam from each vaporization chamber is conducted to turbine stages suitable to its temperature and pressure.

25 It is a further object of this invention to superheat the steam passing to the last stages of the turbine, so that the amount of moisture present in the exhaust will not be sufficient to injure the high speed buckets.

30 It is a further object of this invention to control the rate of flow of the water through the vaporization chambers in accordance with the demand on the system for power.

35 Other objects of this invention, not at this time more particularly enumerated, will be clearly understood from the following detailed description of the same.

The invention is clearly illustrated in the accompanying drawing, in which:—

40 Fig. 1 is a schematic view in elevation with parts broken away, illustrating a power

generating station employing the principle of the present invention.

Fig. 2 is an enlarged view with parts broken away of an underground hot water reservoir and associated structure; and 55

Fig. 3 is an enlarged sectional view of a vaporization chamber.

Fig. 4 is an enlarged sectional view of the reheater.

Similar characters of reference are employed in all of the above described views, to indicate corresponding parts.

Figure 1 illustrates the invention partly in elevation and partly in cross section. A boiler 1 supplies its output of steam during off peak load periods as, for example, during the night time through pipe 2 and valve 3 to turbine 4, which is connected in driving relation to generator 5. A boiler feed pump 6 supplies boiler 1 with feed water. 60 This water is taken from cold well 13 and carried by pipe 14 to feed water pumps 11, 11, 11, 11, 11. Feed water pumps 11 drive feed water through feed water heaters 7, 8, 9 and 10 and through valve 15 and pipe 12 to high pressure pump 6. Steam is bled off turbine 4 into the feed water heaters 7, 65 8 and 10. This steam is much more than sufficient to heat the feed water for boiler 1 and the excess feed water flows by way of valve 17 and pipes 18 and 25 into the huge underground reservoir 20, where it accumulates throughout the off peak period so that it substantially fills chamber 20 at the 70 end of the off peak period. The speed of 75 pumps 11 is such as to deliver the desired quantity of heated water to reservoir 20.

Valve 21 remains open at all times, so that during light load periods live steam from boiler 2 flows into reservoir 20 and acts to 80 heat the hot water as it falls therein up to substantially boiler temperature. At the end of the off peak period as, for example, in the morning, valves 3, 15, and 17 are closed and valves 50, 22 and 26 are opened, so that 85 boiler feed pump 6 receives water substantially at boiler temperature from the huge underground reservoir 20, converts this water into steam at a desired high pressure, 90 for example, 2000 lbs. per square inch and 95 100

supplies this steam by way of pipes 2 and 23, valves 16 and 22, pipe 53, re heater 38 (shown in section in Fig. 4) and water separator 52 and valve 51 to turbine 24. Some 5 steam passes by way of valve 21 and pipe 25 to displace the water leaving reservoir 20. During heavy load periods a deep well pump 88 (see Fig. 2) of the centrifugal type having a series of vanes, the construction 10 of which is well known to those skilled in the art, is preferably used to pump the hot water out of reservoir 20 to the pump 6 and to a vaporization chamber 29 situated adjacent the turbine 24. Pump 88 is driven 15 by an electric motor 77 connected to pump shaft 78. This deep well pump need not be used, however, because the intake pressure of pump 6 and the pressure in vaporization chamber 29 are both considerably 20 low boiler pressure, and such boiler pressure supplied through valve 21 and pipe 25 to reservoir 20 is sufficient to force the hot water in this reservoir out through pipe 19 to vaporization chamber 29 and to the 25 pump as desired. In such instances, the boiler 2 may be forced during heavy load periods so that the increased steam pressure in pipe 25 will all the more readily drive the hot water in reservoir 20 out 30 through pipe 19.

Valve 54 is operated by governor 55 and controls the flow of hot water leaving reservoir 20 in its passage through the vaporization chambers 29, 30, 31, 32, 33, 56, 57, 58, 35 59 and 60. Each of these vaporization chambers are connected through a pipe 35 to a stage of the turbine. A float 79 in each evaporation chamber closes a valve 81 connected to float 79 by rod 80 when the water 40 level drops and opens the valve 81 when the water level rises (see Fig. 3), so as to maintain a constant water level by controlling the out flow.

Turbine 24 drives generator 37 and exhausts into re heater 38 by way of pipes 35 and 41' (see Figs. 1 and 4). Re heater 38 is heated by boiler steam led in by pipe 53 which connects with pipe 23 and condensed high pressure steam flows by pipe 40 to water separator 52. Super heated low pressure steam leaves re heater 38 by pipe 41 and drives low pressure turbine 42. Turbine 42 is mechanically connected to generator 43. Turbine 42 exhausts into condenser 44. Pump 45 pumps the condensate from condenser 44 into cold well 13. The warm water leaving vaporization chamber 60 is also pumped into cold well 13 by pump 61.

60 The operation of this invention is as follows:

1st. During light load periods

Valves 22 and 26 are closed and the large 65 peak load turbines 24 and 42 are shut down.

The major part of the steam leaving boiler 1 flows by way of valve 3 to turbine 4. Four stages of turbine 4 are shown bled into feed water heaters 7, 8, 9, 10 which act as condensers for turbine 4. The feed water is pumped by the four feed water pumps marked 11 and a portion is then pumped by pump 6 into boiler 1. The major portion of the feed water flows through valve 17 and pipe 18 into the steam pipe 25. The series 70 of pumps 11 serve to force this major portion of the heated feed water into pipe 25 against the pressure of the boiler steam therein. Boiler steam flows through valve 21 into pipe 25, so that the feed water leaving pipe 18 is further heated by boiler steam as it flows down into reservoir 20. If the peak load is on the station for a period of, say four hours per day, then reservoir 20 75 may be on storage for approximately twenty hours per day and at the end of that time it will contain most of the heat produced in boiler 1 because the steam bled off of turbine 4 into the feed water heaters 7 to 10 plus the steam supplied through pipe 25 to the 80 hot water going into reservoir 20 is greater than the quantity of steam consumed by turbine 4. A relatively small amount will have been converted to mechanical power by turbine 4 and some heat will have been lost by 85 radiation and thermal conduction.

2nd. During heavy load period

Valve 50 will be opened and valves 3, 17 and 15 will be closed. Turbine 4 and pumps 100 11 will be shut down. The steaming capacity of boiler 1 will be increased, since it is now receiving very hot water from reservoir 20 instead of water 350 degrees Fahrenheit or more cooler from feed water heater 10. This will be apparent when it is realized that water from feed water heater 10 at 350° to 450° F. is heated approximately 105 200° F. or to 650° F. by boiler steam supplied through valve 21 and pipe 25 during light 110 load periods. This water at approximately 650° F. is supplied from reservoir 20 during heavy load periods, while during light load periods the boiler feed water is supplied directly from heater 10 at from 350° to 450° F. If deep well pump 88 is not used the pressure is preferably allowed to rise in reservoir 20 from, say 2,000 lbs. per square inch to, say 2,300 lbs. per square inch by forcing 115 boiler 1 if necessary, or until the increase in pressure exerted through pipe 25 is more than enough to raise hot water in pipe 19 up to governor valve 54. When deep well pump 88 is used it is not necessary to depend on the boiler pressure to raise the water from reservoir 20 to valve 50 as this pump 88 will then do this work. Valve 22 is now opened 120 slowly and steam will pass through pipe 53, through the high pressure coils in re heater 38 and through pipe 40 to water separator 125 130

52. Dry saturated steam passes by way of pipe 71 through governor valve 51 to turbine 24. Valve 51 is opened and closed by arm 62. Arm 62 is pulled down against adjustable threaded stop 73 by spring 64. Hand wheel 72 controls stop 73 and fixes the amount valve 51 may be opened at any desired value. A conventional governor 55 is equipped with a governor arm 74 which 10 rises as the turbine 24 rises above normal speed and vice versa. Hand wheel 72 is preferably adjusted from time to time during heavy load periods, so as to limit the amount of steam flowing to turbine 24 and 15 maintain the desired boiler pressure and hence the pressure in chamber 20 at the required 2,300 lbs. per square inch.

After turbines 24 and 42 have been brought to speed and synchronized, using steam from 20 boiler 1 in the usual manner, valve 26 is opened preferably by hand and my novel method of using very hot water to supply a considerable portion of the necessary energy 25 for peak load comes into operation. Hot water entering governor valve 54 is supplied in amounts required as determined by governor 55. If the speed of turbine 24 is reduced by heavy load, governor arm 74 falls and lowers valve arm 75 through the connecting rod 76. The lowering of arm 75 opens valve 54 and allows water at a temperature of, say 635 degrees Fahrenheit, to flow into vaporization chamber 29. Vaporization chamber 29 is connected by pipe 35 30 to a stage in turbine 24 suitable to the pressure normal to chamber 29.

The water admitted by valve 54 flows in 35 succession through vaporization chambers 29, 30, 31, 32, 33, 56, 57, 58, 59 and 60. The 40 water is pumped from chamber 60 into cold well 13 by pump 61. Pump 61 is required, since chambers 59 and 60 will generally be under less than atmospheric pressure. Bleeder pipes 65, 66, 67, 68 and 69 connect 45 turbine stages to vaporizers 30, 31, 32, 33 and 56. These small bleeder pipes and their associated large steam pipes 35 by-pass a small amount of steam. Each bleeder pipe and its associated steam pipe preferably by-pass one stage. The bleeder pipes connect to grooves around the turbine in the following respects.

1st. The steam bled from the turbine is 50 dried in evaporators 29, 30, 31, 32, 33 and 56 and immediately returned to the turbine to do more mechanical work. Note:—In the conventional method heretofore used this steam has been used to heat feed water.

2nd. The bled moisture is carried 60 through a series of vaporizers and compelled to give up a large percentage of its available heat to do useful work. Note:—In the conventional method heretofore used the bled moisture has been returned to the boiler with the feed water.

It is to be noted that it is not necessary to increase the pressure and temperature in chamber 20 during the peak load operation, if a deep well pump 88 is used to elevate the water from reservoir 20 to valve 54. When 70 the pressure is increased in reservoir 20 during peak load periods, the top water in reservoir 20 heats up approximately 20 degrees Fahrenheit, above the main body of water, and it is not possible to raise this hot water 75 up to valve 54 as solid water, i. e. some of the water will flash into steam. Fig. 2 shows a deep well pump having a shaft 78 passing through a stuffing box 83 into pipe 25 and through a close fitting bearing 84 into pipe 19. A deep well pump 88 of the multi-stage type is mounted on shaft 78 at the bottom 80 of pipe 19.

While many forms of evaporators may be 85 used for 29, 30, 31, etc., Fig. 3 shows a preferred simple form. The evaporator, in this case 30 (Fig. 1), receives hot water from evaporator 29 as indicated by the arrow and exhausts the evaporated steam to the turbine through pipe 35. Small pipe 65 continually feeds in a mixture of steam and water. This steam also passes back to the turbine by way of pipe 35, while the water joins the main body of water. A large float 79 is attached by shaft 80 to valve 81 and 90 opens valve 81 when the water level rises. The water level is kept very close to its normal level shown at 82. The last evaporator 95 60 is made large so as to care for the water flow during a possible brief stoppage of 100 motor 61.

As many changes could be made in the above construction and many apparently 105 widely different embodiments of this invention could be made thereof, it is intended that all matter contained in the above description or shown in the accompanying drawings shall be interpreted as illustrative and not in a limiting sense.

What is claimed is:

1. In a power generating station adapted to carry peak loads, a high pressure boiler, a huge storage reservoir arranged to store water at high temperature and pressure, means for utilizing the greater portion of the energy delivered by said boiler during light load periods to heat water for storage in said reservoir, a plurality of evaporators arranged in series, said evaporators being connected to said storage reservoir during heavy load periods so that hot water from said reservoir is allowed to pass in succession through each of said evaporators, a turbine having a plurality of turbine stages, said turbine being connected to receive steam from said boiler during heavy load periods, connecting pipes serving to connect each of said evaporators to a respective stage of said turbine, whereby a portion of the water from said reservoir, in passing through a respec-

tive one of said evaporators, flashes into steam and is delivered through a connecting pipe to the respective turbine stage, thereby augmenting the steam supplied directly from the boiler to said turbine.

2. In a power generating station adapted to carry peak loads, a high pressure boiler, a huge underground storage reservoir, means for supplying water at high pressure to said reservoir during light load periods, means for utilizing steam from said boiler during light load periods for heating the water supplied to said reservoir to a high temperature, a turbine arranged to be connected to receive steam from said boiler during heavy load periods, a plurality of evaporators connected in series, piping connecting each of said evaporators to a respective stage of said turbine, piping connecting the first of said evaporators to said reservoir for receiving hot water therefrom during heavy load periods, a cold well for receiving water from said evaporators, the water from said reservoir, in passing through said evaporators, being reduced in pressure and temperature in stages, thereby producing steam that passes through said connecting piping to the successive stages of said turbine for augmenting the steam supplied directly from said boiler.

3. In a power generating station adapted to carry peak loads, a high pressure boiler, a huge underground storage reservoir, means for supplying water at high pressure to said reservoir during light load periods, means including a direct pipe connection between said boiler and said reservoir for utilizing steam from said boiler during light load periods for heating the water supplied to said reservoir to a high temperature, a turbine arranged to be connected to receive steam from said boiler during heavy load periods, a plurality of evaporators connected in series, piping connecting each of said evaporators to a respective stage of said turbine, piping connecting the first of said evaporators to said reservoir for receiving hot water therefrom during heavy load periods, a cold well for receiving water from said evaporators, the water from said reservoir, in passing through said evaporators, being reduced in pressure and temperature in stages, thereby producing steam that passes through said connecting piping to the successive stages of said turbine for augmenting the steam supplied directly from said boiler, said direct pipe connection between said boiler and said reservoir serving to maintain boiler pressure within said reservoir at all times, whereby as hot water is supplied to said evaporators, the space left in said reservoir is filled with boiler steam, so that the hot water is delivered from said reservoir at a substantially constant temperature and pressure.

4. In a power generating station, a boiler, a light load turbine connected to receive steam from said boiler during light load periods, a feed water heater connected to said light load turbine for receiving steam from the latter, a huge underground storage reservoir, a cold well, pump means for pumping water from said cold well through said feed water heater and into said reservoir during light load periods, a pipe connection extending between said boiler and said reservoir for supplying steam thereto and to the water fed into said reservoir, to thereby raise such water to substantially boiler temperature and pressure, a multi-stage heavy load turbine connected to receive steam from said boiler during heavy load periods, a plurality of evaporators connected in series, piping connecting said evaporators respectively to respective stages of said turbine, means for connecting the first of said evaporators to said reservoir during heavy load periods, whereby hot water from said reservoir flows through said evaporators in succession and produces steam in each of said evaporators for use in said turbine, and means connecting the last of said evaporators to said cold well.

5. In a power generating station, a boiler, a light load turbine connected to receive steam from said boiler during light load periods, a feed water heater connected to said light load turbine for receiving steam from the latter, a huge underground storage reservoir, a cold well, pump means for pumping water from said cold well through said feed water heater and into said reservoir during light load periods, a pipe connection extending between said boiler and said reservoir for supplying steam thereto and to the water fed into said reservoir, to thereby raise such water to substantially boiler temperature and pressure, a multi-stage heavy load turbine connected to receive steam from said boiler during heavy load periods, a plurality of evaporators connected in series, piping connecting said evaporators respectively to respective stages of said turbine, means for connecting the first of said evaporators to said reservoir during heavy load periods, pump means for pumping hot water from said reservoirs to said evaporators, whereby hot water from said reservoir flows through said evaporators in succession and produces steam in each of said evaporators for use in said turbine, and means connecting the last of said evaporators to said cold well, said pipe connection serving to supply boiler steam to said reservoir as hot water is taken therefrom, whereby such water is delivered from said reservoir at substantially constant temperature and pressure.

6. In a power generating station adapted to carry peak loads, a high pressure boiler,

a huge storage reservoir arranged to store water at high temperature and pressure, means for utilizing the greater portion of the energy delivered by said boiler during 5 light load periods to heat water to boiler evaporating temperature and pressure for storage in said reservoir, means for drawing the hot water from said reservoir during heavy load periods and for utilizing the 10 heat in said drawn water, conduit means for supplying steam from said boiler to said reservoir to displace the hot water thus drawn off, whereby the temperature and pressure of fluid in said huge storage reservoir is maintained substantially at boiler 15 evaporating temperature and pressure at all times.
